UNITED STATES PATENT OFFICE.

KONRAD JAGSCHITZ, OF MAINZ, GERMANY, ASSIGNOR TO MACHINENFABRIK AUGSBURG-NURNBERG, A. G., OF NURNBERG, GERMANY, A CORPORATION OF GERMANY.

CLOSURE FOR DRY GASOMETERS.

Application filed September 24, 1924. Serial No. 739,537.

To all whom it may concern:

Be it known that I, KONRAD JAGSCHITZ, a citizen of Germany, residing at Mainz, Germany, have invented certain new and useful

5 Improvements in Closures for Dry Gasometers, of which the following is a specification.

My invention relates to storage reservoirs for gas and the like and more particularly to 10 waterless gas holders commonly referred to as dry gasometers or gas holders and generally comprising a single tank which is upwardly open and is sealed by means of a floating sealing-disc or closure arranged to 15 rise and fall in said tank in accordance with changes in the gas contents thereof. In gas holders of the indicated class, it is necessary to guide the sealing-disc or closure in its movements in the tank, this result generally 20 having been attained by means of suitable truss-work connected with the closure and carrying guide-rollers which travel along the inner surface of the tank or along special shell posts provided therein. In holders 25 particularly of large diameter, which require a correspondingly large sealing disc, the arrangement of the truss-work results in an unstable equilibrium of the floating closure mass.

30 The object of the present invention is to provide an improved and novel arrangement of closure in which the centre of buoyancy is located above the centre of gravity and the sealing-disc is not only properly guided and 35 maintained in the desired horizontal position, but further a stable equilibrium of the floating closure mass is obtained.

The invention will be fully described hereinafter and the features of novelty will be 40 pointed out in the claims.

In the accompanying drawings, which show an example of an existing arrangement and several examples of the invention without defining its limits, Fig. 1 is a diagrammatic, fragmentary sectional elevation showing an existing construction of sealing-discs for dry gasometers and Figs. 2 and 3 are similar views illustrating two arrangements of the novel construction.

As shown in Fig. 1, the tank which generally speaking is in the form of an upright, upwardly open shell, is indicated at g , it being understood that a gas inlet g' and a

gas outlet g'' are connected with said tank in the customary manner as, for instance, indicated in Fig. 1. The closure comprises a sealing-disc k of any conventional construction and which is provided at its periphery with a liquid seal o of any usual form adapted to partake of the rising and falling movements of said disc k and to maintain a gas-tight closure between the same and the shell g . For guiding the closing-disc k in its vertical movements, rollers m are journaled at spaced intervals upon a truss-work n which projects upwardly from the disc k and in the complete structure extends circumferentially thereof. The rollers m generally are arranged to travel lengthwise of shell posts or other suitable guiding members located at the proper points in the shell. The closure thus comprises a floating structure which floats upon the gas contained in the tank and consequently includes not only a center of gravity but also a center of buoyancy, the relative location of which affects the stability of said closure.

Because of the stresses to which the closing-disc k is subjected, in practice, it is necessary to brace the same in order that such stresses may be adequately resisted. As shown in Fig. 2, the disc k is accordingly provided with stiffening-trusses h located below and depending from said disc, it being understood that the trusses h are secured to said disc in any convenient way.

The construction shown in Fig. 3 differs from that of Fig. 2 by having the liquid-seal o' located at a greater distance below the disc k' than is the liquid-seal o of Fig. 2; with the arrangement illustrated in Fig. 3, the truss-work n' , which corresponds to the truss-work n of Fig. 2, projects to a lesser extent above the disc k' and is thus kept low with respect to said disc. It will be noted that, even though the distance p between the centres of the guide rollers m in each of the two forms is the same, the height s of the closure in Fig. 3 is less than the height r of the closure shown in Fig. 2. The stability of structure shown in Fig. 3 is thus even greater than that of the form shown in Fig. 2. To complete the closure of Fig. 3 between the disc k' and the liquid-seal o' a vertical, cylindrical shell v is connected with the stiffening stresses h' . The

latter correspond to the trusses h of Fig. 2 and are likewise located below and depend from the sealing-disc k' to which they are fastened in any suitable manner.

- 5 With the novel arrangement of stiffening-trusses shown in Figs. 2 and 3, the centre of gravity i of the entire closure is located below the discs k or k' and consequently is below the centre of buoyancy of the closure 10 which is indicated at l . The closure is therefore in stable equilibrium and will accordingly always possess the inherent property of remaining in a horizontal position while 15 ascending and descending in the shell g .
- 15 The guide rollers m and m' as a result are relieved of considerable strains and forces and the ascent and descent of the closure is accomplished with a minimum of friction and with the sealing disc k or k' always in 20 a horizontal position of maximum efficiency.
- 25 To clearly show the advantages of the present novel arrangement over an existing construction, reference is made to Fig. 1 of the drawings in which the stiffening trusses b are located upon and above the sealing-disc a , guide rollers f being mounted upon truss-work e which forms part of the trusses b and are likewise located above the disc a . With the arrangement illustrated in Fig. 1, 30 the center of gravity c of the closure is located above the center of buoyancy d and the closure is therefore in unstable equilibrium, which is resisted by the rollers f and consequently places the same under considerable strain and forces said rollers into 35 heavy frictional engagement with the shell-posts or equivalent guiding means along which said rollers are arranged to travel.
- 40 The present novel construction overcomes these objectionable features in an efficient manner and provides a closure of maximum serviceability.

Various changes in the specific forms

shown and described may be made within the scope of the claims without departing 45 from the spirit of my invention.

I claim:

1. In a dry gasometer, the combination of a tank, a floating closure for sealing said tank and adapted to rise and fall therein, 50 means for guiding said closure in its vertical movements in said tank and bracing means for stiffening said closure combined therewith in a manner to locate the center of gravity of said closure below the center of 55 buoyancy thereof.
2. In a dry gasometer, the combination of a tank, a floating closure for sealing said tank and adapted to rise and fall therein, 60 said closure comprising a sealing-disc, a seal at the periphery of said disc, guide-rollers mounted upon said disc for guiding the same in its vertical movements and stiffening trusses located below and depending from said disc and arranged so as to 65 locate the center of gravity of said closure below the center of buoyancy thereof.
3. In a dry gasometer, the combination of a tank, a floating closure for sealing said tank and adapted to rise and fall therein, 70 said closure comprising a sealing-disc, guide-rollers mounted upon said disc for guiding the same in its vertical movements, stiffening trusses located below and depending from said disc and arranged so as to 75 locate the center of gravity of said closure below the center of buoyancy thereof, an annular liquid seal carried by said closure and located approximately at the level of the lower chord of the stiffening trusses and a 80 cylindrical shell surrounding said stiffening trusses between said disc and said seal.

In testimony whereof I have hereunto set my hand.

KONRAD JAGSCHITZ.
